UNITED STATES PATENT OFFICE.

JOHN C. HIRSCH, OF ALLEGHENY, PENNSYLVANIA, ASSIGNOR OF TWO-THIRDS TO FRANK HUCKESTEIN, OF SAME PLACE, AND THEODORE HIRSCH, OF AVALON, PENNSYLVANIA.

DESIGN FOR A CASING FOR INDICATORS.

SPECIFICATION forming part of Design No. 26,772, dated March 16, 1897.

Application filed September 9, 1896. Serial No. 605,384. Term of patent 14 years.

To all whom it may concern:

Be it known that I, JOHN C. HIRSCH, a citizen of the United States, residing at Allegheny, in the county of Allegheny and State

5 of Pennsylvania, have invented and produced a new and original Design for Indicators for Measuring-Faucets, of which the following is a specification, reference being had to the accompanying drawings, showing a part thereof.

o Figure 1 is a top or face view of an indicator showing my design, and Fig. 2 is a side view thereof.

The leading features of my design consist in a box or casing for indicators having formed 5 on the top face thereof three dials. One large dial is located at one end of the box or casing, and the other two smaller dials are located side by side on the opposite end of the box or casing close to the large dial.

o A is the box or casing, which is provided with a bottom *b* thereon. A large dial *c* is

formed on the top face *a* of the box or casing A. Two smaller dials *d e* are formed side by side on the top face *a* of the box or casing A, adjacent to the large dial *c*.

25 The design, as set forth and illustrated in the drawings, is adapted to fit on top of a measuring-faucet having a handle connected to a shaft, upon which are pinions, which are adapted to revolve a bevel-gear connecting with the mechanism within the indicator.

30 What I claim is—

The design for a box or casing for an indicator, substantially as herein shown and described.

35 In testimony that I claim the design above set forth I affix my signature in presence of two witnesses.

JOHN C. HIRSCH.
